(57) **CLAIM**

The ornamental design for set of gripping panels for bag closure, as shown and described.

DESCRIPTION

FIG. 1 is a top, front, and right side perspective view of gripping panels in an open configuration; FIG. 2 is a front view thereof, the rear view being identical to the front view;

FIG. 3 is a right side view thereof, the left side view being identical to the right side view;

FIG. 4 is a top view thereof;

FIG. 5 is a bottom view thereof; and,

FIG. 6 is an enlarged, cross-sectional view taken in the direction of line 6-6 in FIG. 2.

In the drawings, the broken lines depict environmental subject matter only that forms no part of the claim.

The claim is limited to the elements shown in solid line.
